DESIGN FOR A DART GAME BOARD

Henry Elton Pease, Chicago, Ill.

Application August 31, 1942, Serial No. 108,087

Term of patent 3½ years

To all whom it may concern:

Be it known that I, Henry Elton Pease, a citizen of the United States, residing at Chicago, in the county of Cook and State of Illinois, have invented a new, original, and ornamental Design for a Dart Game Board, of which the following is a specification, reference being had to the accompanying drawing, forming a part thereof.

In the drawing,

Fig. 1 is a front elevational view of a dart game board, showing my new design; and

Fig. 2 is a side elevational view thereof.

I claim:

The ornamental design for a dart game board, as shown.

HENRY ELTON PEASE.
